SOCKET LINING AND METHOD OF MAKING SAME

Application filed January 18, 1929. Serial No. 333,480.

My invention relates to a new and improved method of manufacturing an electric-light socket lining, and to a new and improved socket lining.

- 5 One of the objects of my invention is to provide a socket lining which shall have high resistance to the action of heat so that the said lining will not carbonize and become brittle when it is heated.
- 10 Another object of my invention is to provide a simple and efficient method of providing an insulating socket lining for the sockets of incandescent electric lamps.

Another object of my invention is to provide a socket lining for this purpose which shall include asbestos or asbestos paper in a new and improved form.

Another object of my invention is to provide a socket lining having an interior layer made of asbestos, and an outer layer made of paper such as kraft paper.

Other objects of my invention will be set forth in the following description and drawings which illustrate a preferred embodiment thereof, it being understood that the above general statement of the objects of my invention is intended to generally explain the same and not to limit it in any manner.

Fig. 1 is an elevation showing a strip of paper employed for making the improved lining.

Fig. 2 is a view similar to Fig. 1 showing a sheet of asbestos paper utilized for making the interior layer of the socket.

Fig. 3 shows how the sheets of material illustrated in Figs. 1 and 2 are glued together.

Fig. 4 is an end view of the composite material shown in Fig. 3.

Fig. 5 is a sectional view of the spiral tube which is rolled from the composite material. This spiral tube is formed of a plurality of parallel layers of composite material.

Fig. 6 is a vertical sectional view of the tube which is rolled from the composite material.

Fig. 7 is a vertical sectional view showing how the tube illustrated in Fig. 6 is formed into the final shape.

Fig. 8 is an elevation of the completed socket lining.

The sockets used for holding incandescent electric lamps must have an insulator lining between the outer socket shell, and the inner screw shell which carries the electrical connections. When the incandescent lamps have a high candle power so that the temperature of the socket is correspondingly raised, the heat causes the ordinary paper linings to carbonize and become brittle and fall out of position, so that the insulating protection is injured or destroyed.

Asbestos paper can withstand the high temperature but it is too brittle to be formed into linings, and in addition, it has other properties which make it difficult to form a lining therefrom.

According to my invention, a sheet of suitable paper 1, such as manilla paper or what is known in the trade as kraft paper is fastened by means of a suitable adhesive, or by any other means, to a sheet of asbestos paper 2. As shown by the stippled lines G, the grain of said paper is preferably parallel to the long side thereof. The tubes which are later mentioned may be formed from the sheet of composite material shown in Fig. 3, which is 15 inches long and 12 inches wide. If desired, the edges of the long sides of both sheets of material may be extended beyond each other $\frac{1}{2}$ inch to facilitate the tube rolling operation. This is shown in Fig. 4. A tube T is now rolled from this composite material. The grain of said paper and the fibres of the asbestos paper are preferably parallel to the longitudinal axis of the tube, as shown by the lines G in Fig. 6. The tube T is 15 inches long and it has a diameter which is equal to the diameter of the widest part of the finished socket. The diameter of the widest part of the finished socket is ordinarily $1\frac{1}{8}$ inches and the diameter of the narrowest portion is ordinarily about $1\frac{1}{4}$ inches. The tubes are formed by means of any suitable tube-rolling machine which is not shown in the drawings, as in itself such machine is old and well known. Such machines ordinarily have a pair of paste rolls through which the composite sheet passes,

and revolving shaft on which the paper is rolled. The advantage of causing the thin edge of the asbestos paper to overlap the edge of the kraft paper is that the thin edge of the asbestos paper will start to quickly roll up into tube form as soon as it meets the revolving shaft. The kraft paper has a chamfered or "deckle" edge to make a smooth and almost invisible seam. The asbestos paper in the interior of the tube covers and protects the edge of the kraft paper. The tube T which is thus rolled and which is 15 inches long, is cut into any suitable number of shorter tubes. Ordinarily, these tubes are 2 inches high, some allowance being made for waste, so that seven tubes are cut from the tube which has been rolled. The section T' which has thus been cut from the long tube T is now placed upon a pin P whose shape corresponds to the shape of the finished socket lining S. An outer die member D is now forced downwardly upon the section T' as illustrated in Fig. 7. This contracts and crimps the upper portion of the section T' so as to form the completed article shown in Fig. 8. This operation may be performed while the section T' is at ordinary room temperature.

The exterior of the contracted portion of the tube is quite smooth. It would be impossible to directly reduce the diameter of a tube formed from asbestos alone because the asbestos has fibre which is so weak, that such fibre would be forced downwardly by the die instead of passing through the die to be compressed into the smaller diameter required. However, the improved lining has the asbestos material substantially undistorted in a direction which is longitudinal, or parallel to the axis of the lining. That is, the asbestos material forms the internal wall of the lining, instead of being carried through the die. I do not wish to exclude from the scope of the invention a lining in which the asbestos material may have been somewhat distorted in a direction parallel to the axis, as it is sufficient if the asbestos material forms a continuous inner wall of the socket lining. By using said paper as the outside layer of the tube section, the diameter thereof can be reduced, and the reduced portion can be compressed into the proper shape. I prefer to have 60% of the weight of the socket S consisting of the asbestos, the remaining 40% consisting of said paper, which forms the outside layer of the completed article S.

It is advantageous to have the grain of said paper parallel to the longitudinal axis of the tube because this enables the composite tube section to be rapidly and efficiently reduced in diameter.

It is likewise desirable to have the die work performed directly on said paper because the

asbestos would scratch the die, while said paper eliminates this disadvantage.

While I have specifically mentioned the use of kraft paper, and while I have specifically mentioned certain proportions, this is intended only by way of illustration and I do not wish to be limited to the details given by way of illustration.

Generally speaking, the improved socket lining consists of a composite material comprising asbestos and an outer face layer made of non-asbestos material which can be readily compressed and shaped by means of a die. The use of the asbestos and paper, in the proportions above mentioned, produces a socket lining which is very flexible so that it may be subjected to heavy pressure without being injured. In this respect, the article made according to my invention is superior to that made of fiber because the fiber linings are brittle.

While I have illustrated a preferred method for making the completed socket lining, I do not wish that the claims for the article of manufacture should be limited to the method disclosed herein.

I have shown a preferred embodiment of my invention, but it is clear that numerous changes and omissions could be made without departing from the spirit of my invention.

I claim:

1. A tubular and flexible lining for the socket of an incandescent lamp, said lining having longitudinally disposed portions of different diameter, said lining being made of a composite material which includes asbestos and bendable non-asbestos material, the face layer of said lining being made of said non-asbestos material, one end portion of said lining having a smaller lateral diameter than the other end portion of said lining, the end portion of said lining which has the smaller diameter being inwardly and laterally compressed, the asbestos in said end portion of smaller diameter being substantially undistorted in a direction parallel to the axis of the lining.

2. A tubular and flexible lining for the socket of an incandescent lamp, said lining having longitudinally disposed portions of different diameter, said lining being made of a composite material which includes asbestos and bendable paper material, the face layer of said lining being made of said paper material, one end portion of said lining having a smaller lateral diameter than the other end portion of said lining, the end portion of said lining which has the smaller diameter being inwardly and laterally compressed, the asbestos in said end portion of smaller diameter being substantially undistorted in a direction parallel to the axis of the lining.

3. A tubular and flexible lining for the socket of an incandescent lamp having end

portions of different diameter, said lining being made of composite material which includes asbestos, the outside layer of said lining being made of paper whose grain is substantially parallel to the longitudinal axis
5 of the lining, the portion of said lining which has the smaller diameter being inwardly and laterally compressed, the asbestos in said end portion of smaller diameter being substantially undistorted in a direction parallel
10 to the axis of the lining.

4. A tubular lining for the socket of an incandescent lamp, said lining being formed of a spirally wound composite sheet which includes asbestos and non-asbestos material,
15 one end of said lining being laterally and inwardly compressed, the asbestos in said end portion being substantially undistorted in a direction parallel to the axis of the tubular lining.

20 5. A tubular lining for the socket of an incandescent lamp, said lining being formed of a spirally wound composite sheet which includes asbestos and paper, the face layer of said lining consisting of paper, one end of
25 said lining being laterally and inwardly compressed, the asbestos in said end portion being substantially undistorted in a direction parallel to the axis of the tubular lining.

30 In testimony whereof I affix my signature.
LEWIS D. CHRISTIE.
